Primary Examiner — Cathron Brooks*Assistant Examiner* — Barbara Fox(74) *Attorney, Agent, or Firm* — Birch, Stewart, Kolasch & Birch, LLP**CLAIM**

The ornamental design for a frozen confection, as shown and described.

DESCRIPTION

FIG. 1 is a perspective view of a frozen confection showing my new design; and,

FIG. 2 is a cross-sectional view taken in the direction of line 2—2 of FIG. 1.

The broken lines shown in the drawings represent environmental structure and form no part of the claimed design.
